(57) **CLAIM**

The ornamental design for an accumulator charging apparatus as shown and described.

DESCRIPTION

FIG. 3.1 is a front, top and left side perspective view of an accumulator charging apparatus for an electrical vehicle; FIG. 3.2 is a top plan view thereof; FIG. 3.3 is a bottom plan view thereof; FIG. 3.4 is left side elevation view thereof; FIG. 3.5 is a right side elevation view thereof; FIG. 3.6 is a front elevation view thereof; FIG. 3.7 is a rear elevation view.

The dashed broken lines and the ghosted portions of the accumulator charging apparatus enclosed by the dashed broken lines form no part of the claimed design.

Color forms no part of the claimed design.
